COMBINED ADDRESS BOOK AND MAGNIFYING LENS

Richard-Wilhelm Heydemann, Via Tagliaferri Blocco A,
CH-6911 Campione-Lugano, Switzerland

Filed Feb. 2, 1970, Ser. No. 21,211

Claims priority, application Germany Oct. 28, 1969

Term of patent 14 years

Int. Cl. D19—04

U.S. Cl. D97—2

Fig. 1

Fig. 3

FIG. 1 is a top perspective view of a combined address book and magnifying lens showing my new design;

FIG. 2 is a similar view thereof as it appears with the cover in the open position and the magnifying lens removed from its pocket; and

FIG. 3 is a bottom perspective view of the combined address book and magnifying lens shown in FIG. 1.

I claim:

The ornamental design for a combined address book and magnifying lens, substantially as shown.
